UNITED STATES PATENT OFFICE.

ROBERT M. CLARK, OF NEWTON CENTER, MASSACHUSETTS, ASSIGNEE TO CENTRE
RAILWAY SIGNAL COMPANY, OF PITTSBURGH, PENNSYLVANIA, A CORPORATION
OF NEW JERSEY.

RAILWAY SIGNAL-FUSES.

1,129,644.

Specification of Letters Patent.

Patented Feb. 23, 1915.

Application filed May 5, 1914. Serial No. 836,546.

To all whom it may concern:

Be it known that I, ROBERT M. CLARK, citizen of the United States, residing at Newton Center, in the county of Middlesex and State of Massachusetts, have invented 5 certain new and useful Improvements in Railway Signal-Fuses, of which the following is a specification, reference being had therein to the accompanying drawing.

- 10 My invention relates to improvements in Railway Signal Fuses, and pertains to certain improvements for securing a spike plug, in one end of the fusee tube. Heretofore, the spike plugs used in the ends of fuses have been secured in the open end of the fusee tube, and the plug when made of metal glued within the tube, and when made of wood is glued or tacked, or both, to the open end of the tube.
- 15 My present improvement consists in holding the plug within the fusee tube by turning the end wall of the tube inward and gluing it to the outer end of the plug, and also gluing the side of the plug to the inner wall 20 of the tube, and to pack the burning or signal compound within the tube against the inner end of the plug, thus supplementing the glue in holding the plug against inward movement within the tube.
- 25 In the accompanying drawings Figure 1 30 is a sectional view of a fusee showing my improved manner of holding the spike plug within one end thereof. Fig. 2 is a perspective view of a fusee with the spike plug held therein by my improvement. In carrying out my improvement, the usual fiber or paper tube 1 is employed and the wall thereof is turned or crimped inward, as shown at 2, forming a closure with a central opening 3, through which the spike 4 passes.
- 35 The spike 4, is carried by the plug 5. This 40 plug is of a contour and size to fit the interior of the tube 1.

In the manufacture of the fusee with my 45 improved method of holding the plug in position, one of the two following methods may be followed. The tube 1 may first have the burning or signal compound 6 packed therein and then a portion thereof removed or drilled from one end sufficiently 50 to receive the plug 5 and a part of the tube to extend beyond the plug 5. Then the projecting end of the tube coated with a layer of glue 7; the plug placed in position, the inner end thereof abutting against the com-

pound 6 and then the extended end of the tube crimped and turned inward by a suitable revolving tool downward upon the outer end of the plug 5 and around the spike 4, the glue serving to unite and hold the in-turned end 2 in position against the outer end of the plug, thus preventing the plug 5 from being detached from the tube.

Another manner of applying my improvement to the fusee is to first crimp and turn 55 inward the end of the tube 1 to form a closure 2 with an opening 3, through which the spike 4 can be pushed. Glue can then be applied to the end of the plug 5 and the plug pushed in from the opposite end of the tube and then the burning or signal compound 6 packed against the plug, forcing it in contact with the turned in end or closure 2, thus gluing or aiding the closure 2 to the plug. In either event the closure will 75 prevent the plug from being withdrawn from the fusee and the burning or signal compound 6 will prevent the plug from being driven inward within the tube.

This improvement provides a cheap and 80 efficient manner of securing the spike plug within the fusee tube and at the same time produces a fusee with a finished and attractive spike end.

While I have described my invention as 85 particularly intended for a railway time burning signal fusee, yet it is capable of use in connection with devices consisting of a paper tube carrying a burning compound when it is desired to provide that device with 90 a spike by means of which it can be supported in an upright position.

Having thus described my invention, what I claim and desire to secure by Letters Patent is:

1. A spike end fusee comprising a fiber tube, a plug fitting within one end thereof and having at its outer end a projecting spike, the end wall of the fusee crimped and turned inward against the outer end of the plug and cemented thereto, the spike passing through the crimped and turned in end of the tube, and a burning compound within the tube to receive the inward end thrust of the plug when the spike is forced into an 105 object for supporting the fusee.

2. A spike end fusee, comprising a fiber tube, a plug fitting within one end thereof and carrying at its outer end a projecting spike, the end walls of the tube crimped and 110

turned inwardly against the end of the plug and around the spike and engaging the side of the spike, substantially as shown and described.

- 5. 3. A spike fusee comprising a fiber tube, a plug fitting within the end thereof and carrying at its outer end a projecting spike, the end walls of the tube crimped and turned inwardly against the end of the plug and around the spike and engaging the sides of the spike and a cementing composition between the tube and the plug, substantially as shown and described.
- 10 4. A spike end fusee comprising a fiber

tube, a plug fitting within the end thereof 15 and carrying at its outer end a projecting spike, the end walls of the tube crimped and turned inwardly against the end of the plug around the spike and a cementing composition between the tube and the crimped end 20 of the plug.

In testimony whereof I hereunto affix my signature in the presence of two witnesses.

ROBERT M. CLARK.
